(57) **CLAIM**

What is claimed is the ornamental design for an orthopedic device, as shown and described.

DESCRIPTION

FIG. 1 is a front view of an orthopedic device illustrating the new design;

FIG. 2 is a rear view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top plan view thereof; and,

FIG. 8 is a bottom plan view thereof.

In FIGS. 1 and 2, the human hand is shown in broken lines for illustrative purposes only and forms no part of the claimed design.
